UNITED STATES PATENT OFFICE.

SAMUEL HOLSTEIN, OF NEW YORK, N. Y.

UNDERGARMENT.

1,104,047.

Specification of Letters Patent.

Patented July 21, 1914.

Application filed August 5, 1913. Serial No. 783,222.

To all whom it may concern:

Be it known that I, SAMUEL HOLSTEIN, a citizen of the United States, residing at New York, in the county of New York and 5 State of New York, have invented certain new and useful Improvements in Undergarments; and I do declare the following to be a full, clear, and exact description of the invention, such as will enable others skilled 10 in the art to which it appertains to make and use the same.

This invention relates to an attachment for shirts and is designed to be used on either outer or under garments of this character.

The object of the invention is to provide a tailless shirt with a legless drawer attachment so constructed as to prevent the shirt from working upwardly out of the 20 trousers when the attachment is used on an outer garment and which when employed avoids the necessity of wearing drawers and yet will fully prevent chafing at the crotch.

With this and other objects in view, the 25 invention consists of certain novel features of construction, combination and arrangement of parts as will be more fully described and claimed.

In the accompanying drawings: Figure 1 30 represents a front elevation of a shirt equipped with this improved attachment; Fig. 2 is a similar view of the parts forming the attachment separated and arranged in juxtaposition; Fig. 3 is a longitudinal section taken on line 3—3 of Fig. 1.

In the embodiment illustrated, a tailless shirt 1 is shown constructed similarly to the ordinary blouse shirt waist and having this improved drawer attachment 2 secured to 40 the lower edge of the rear portion thereof. This attachment may be either permanently or removably secured to the shirt preferably the latter and by any suitable means.

The attachment as shown comprises two 45 pieces of fabric 3 and 4 which may be either woven or knit having their inner edges 5 which are designed to be stitched together curved inwardly from the ends of each strip toward the center thereof so that when said members 3 and 4 have been joined together 50 at their inner edges they will form a legless drawer which will comfortably fit the crotch of the wearer, the lower folded edge 6 thereof being inclined from the center toward 55 the edges of the attachment as is shown

clearly in Fig. 1. The ends of these connected pieces 3 and 4 being wider than their central portions afford ample protection to the wearer and are preferably provided at their upper outer corners with inclined flaps 60 7 and 8 having coöperating fastening elements for securing the garment together over the hips. The free ends of the front portion of the connected members 3 and 4 are also provided with button holes or other 65 fastening devices for coöperation with corresponding fastening elements carried by the front of the shirt, whereby said drawer attachment is detachably connected at the front portion thereof with the front portion 70 of the shirt to provide for the quick removal of the garment when desired.

A longitudinal slit 9 is preferably formed in the front portion of the drawer attachment and is preferably closed by a suitable 75 fastening such as a button and button hole the purpose of which will be obvious. The ends of this drawer attachment may be provided with longitudinally spaced fastening elements to provide for the adjustment of 80 the device to comfortably fit wearers of different sizes.

In the use of the device, the rear portion 85 thereof being secured to the back of the shirt, the shirt may be applied in the ordinary manner and the attachment after being passed between the legs of the wearer, may be secured in position by fastening the free end of the front portion thereof to buttons or other fastening elements secured to 90 the front of the shirt in position to coöperate with the fastening elements on the attachment. The fastening elements at the hip may then be secured and the garment will then be in operative position.

The corners of the connected members 3 and 4 are preferably inclined in relation to the outer side edges thereof to provide for the proper fitting of the flaps 7 and 8 over the hips of the wearer.

By curving the inner edges of the strips 3 and 4 inwardly as shown, it will be obvious that when these curved edges are stitched together and the attachment folded transversely intermediate of its ends, the fold thereof will incline downwardly and outwardly from said central seam toward the free edges of the attachment to comfortably fit the legs of the wearer and without the necessity of forming any seam at this point 110

in the garment which would be objectionable, in that it would be liable to chafe at this point.

While I have described my invention with 5 more or less minuteness as regards details and as being embodied in certain precise forms, I do not desire to be limited thereto unduly any more than is pointed out in the 10 claims. On the contrary, I contemplate all proper changes in form, construction and arrangement, the omission of immaterial elements and substitution of equivalents as circumstances may suggest or render expedient.

What is claimed as new is:—

15. 1. A drawer attachment for shirts composed of two strips of material having their inner edges curved inwardly from their opposite ends toward the centers of the strips,

said curved edges being secured together, and means at the opposite ends of said strips 20 for securing the attachment in operative position.

2. A drawer attachment for shirts composed of two strips of material having their inner edges curved inwardly from their opposite ends toward the centers of the strips, 25 said curved edges being secured together, said strips having their corners beveled and provided with fastening elements.

In testimony whereof I have hereunto set 30 my hand in presence of two subscribing witnesses.

SAMUEL HOLSTEIN.
